UNITED STATES PATENT OFFICE.

ALEXANDER FRITZ, OF MANAYUNK, PENNSYLVANIA.

PAPER-HANGING MACHINE.

Application filed September 14, 1923. Serial No. 662,690.

To all whom it may concern:

Be it known that I, ALEXANDER FRITZ, a citizen of United States, residing at Manayunk, Philadelphia, in the county of Philadelphia and State of Pennsylvania, have invented certain new and useful Improvements in Paper-Hanging Machines; and I do declare the following to be a full, clear, and exact description of the invention, such 10 as will enable others skilled in the art to which it appertains to make and use the same.

This invention relates to that class of inventions commonly known as paper-hanging machines, the same having more specific reference to a machine of this class which includes means for holding and permitting unwinding of the roll of paper so as to permit it to pass over a paste discharge slot in a 15 container to permit paste to be automatically applied to the reverse side of the paper, together with a brush for applying paper to the wall and a knife for severing the paper when the end of a single stretch 20 is reached. As is usual, all of the details for accomplishing these ends are mounted on a single portable hand-operated supporting device in such a manner as to permit them to operate in the proper order for facilitating the hanging of paper.

It is one of the principal aims of the invention to generally improve upon devices of the above-named type by providing one of extreme simplicity and durability where- 25 in the parts are arranged in such a manner as to insure effective operation and to provide a highly practical device.

More specifically speaking, it is a further and a very important aim to provide a machine of this kind which embodies novel means for coating with that portion of a 30 strip of paper which passes over the slot in the container, this means being adjustable and manually controlled so that the thickness of the paste applied to the reverse side 35 of the paper can be accurately governed according to the grade and strength of paper used.

Another feature of the invention is in the 40 method of mounting the paste container or tank so that the same can be rotated about a pivot and held in various adjusted positions for facilitating the discharge of the 45 paste to insure that every bit of the paste can flow from the container regardless of

the angle at which the supporting device is held.

A still further feature of the invention resides in the provision of a soft-hair roller brush which is insured of positive rotation 60 to prevent dragging of the brush on the paper which would have a tendency to tear it.

Other objects and advantages of the invention will be apparent during the course 65 of the following description.

In the accompanying drawings forming a part of this specification and in which like numerals are employed to designate like parts throughout the same:

Figure 1 is a side elevation of a paper-hanging machine constructed in accordance with this invention, a portion of one of the wall engaging rollers being broken away to disclose one of the details.

Figure 2 is a top plan view of the machine.

Figure 3 is a central longitudinal section taken on the line 3—3 of Fig. 2.

Figure 4 is a transverse section taken on 80 the line 4—4 of Fig. 3.

Figure 5 is an enlarged detail section taken on the line 5—5 of Fig. 1.

Figure 6 is an enlarged detail section taken on the line 6—6 of Fig. 2.

Figure 7 is a detail sectional view of a special design of brush to be used in corners of the room.

Figure 8 is a detail perspective view of a tool used in conjunction with the machine.

Referring to the drawings in detail, the numeral 1 designates a handle, to the forward end of which a substantially U-shaped metal frame 2 is secured. This frame forms a supporting device for the several details 95 to be hereinafter described.

Mounted at the inner end of the frame and journaled in bearings in the side bars thereof is a comparatively small removable rod 3 upon which the wall paper P is wound, 100 the convolutions thereof being held tightly together and prevented from loosely unwinding by means of a flat spring 4 which rests against the roll of paper. Adjacent the roll of paper and secured between the 105 upper portions of the side bars of the frame is a guide rod 4^a over which the strip of paper is trained. After passing over this guide, the paper passes around the cylindrical paste container 5 and across a longitu- 110

dinal paste discharge slot 6 in one side thereof. On opposite sides of this slot are small guide rods 7 which are disposed in spaced parallelism with the slot, the paper engaging these rods in its travel across the slot. It may be conveniently mentioned here that it has been found highly desirable to control the amount of paste applied to the reverse side of the strip of paper according to grade and strength of the paper. To accomplish this result I have provided unique means which in its preferred form comprises a bar 8 provided with a contact strip or facing of rubber 9 which engages and forces the adjacent portion of the paper into the aforesaid slot 6, insuring that the paste will be evenly distributed over the entire width of the strip of paper as it passes across the slot. It is desirable that this presser-bar, as it may conveniently be termed, is to be yieldably mounted and in carrying out this end I simply provide a yoke 10 having apertures adjacent its ends through which guide pins 11 extend, these pins being surrounded by coiled springs 12 which serve to maintain the presser-bar in yieldable engagement with the paper.

So that the thickness of the paste applied may be accurately governed, I provide means for varying the pressure of this bar on the paper and in its preferred embodiment, the means comprises a lever 13 which is pivotally connected between its ends with ears 14 on the aforesaid yoke. The free end 35 of this lever passes through an aperture in a plate 15 which is connected at its ends with the aforesaid guide pins 11. Consequently when the lever is rocked upon its pivot in a direction toward the roll of paper, 40 the presser-bar will be retracted and pressure upon the paper will be relieved. Hence, a greater amount of paste will be applied to the paper. Not only is it desirable to regulate the paste in this manner, but it is desirable that the same amount of paste 45 will be applied to the strip throughout its length. Therefore, I have provided means for maintaining the lever in a set position and this means preferably comprises a wire or other flexible element 16 which is connected to one end of the lever and is passed over a pulley 17. This wire is provided on its free end with a ring or other suitable device 18 which is adapted to be selectively engaged with one of the pins 19 on the aforesaid handle. It is evident that when the ring is engaged with the foremost pin, the pressure of the presser-bar will be greater than when the ring is engaged with one of the remaining two pins. It is of course apparent that the laterally directed ends of the aforesaid yoke will be provided with slots 20 to permit movement of the guides 50 21 on the ends of the presser-bar.

After the paper has passed over the slot

to permit paste to be applied thereto, it passes over another guide rod 22 then over spaced bars 23 which have their surfaces rounded, and finally over a rotary bristle brush 24 to permit its being pressed against the wall and attached thereto. At this point, attention is directed to the fact that the brush 24 is provided with comparatively soft bristles and the trunnions thereof extend beyond the bearings in the side bars of the frame in which they are journaled, these extending ends carrying soft rubber wall engaging wheels 25 which serve to insure positive rotation of the brush and prevent slipping of the wheels. It is to be noted that the diameter of the latter is greater than that of the wheel, but when the device is in use, the soft bristles flex sufficiently to permit the working bristles to become disposed in a plane with the periphery of the wheels when pressure is exerted on the brush. Without the wheels the brush would probably drag over the paper in a great many places and if the paper were overly wet, it would probably tear. However, by having a soft-bristle brush and insuring positive rotation thereof by providing wheels for engaging the wall, possible tearing of the paper is eliminated.

Another detail of the invention yet to be described is the cutting knife which serves to sever the paper when the end of a stretch is reached. The knife is here indicated by the reference character 26 and it will be seen from the drawings that it is horizontally disposed and cooperates with the aforesaid bars 23 in cutting the strip of paper. It is desired that the action of this knife be more or less automatic in operation and for this reason I have provided 95 spring means for actuating the same. Directing attention now to Fig. 5, it will be seen that one end of the knife blade is rigidly secured to a vertical spring-rotated spindle 27, the normal tendency of which is to swing the knife to operative position. For the purpose of preventing movement of the knife during the papering operation, I provide a cord-controlled spring-pressed latch 28 (seen clearly in Fig. 6) which engages with a downturned edge portion 29 on the knife. The cord 28^a for controlling this latch is led over suitable guides on the frame and terminates in a convenient point adjacent the handle to permit it being pulled for permitting operation of the knife.

Difficulty is sometimes experienced in fully emptying the container of paste and for this reason I have mounted the same on a pivot shaft 30 journaled in bearings in the side bars of the aforesaid frame. This arrangement permits tilting of the tank to the proper angle with respect to the handle to insure that all paste will be discharged.

It is desirable to hold the tank in various adjusted positions and for this purpose I increase the thickness of one of the end walls of the tank as shown at 31 (Fig. 4) and then 5 provide this thickened portion with sockets into which the inner end of a screw 32 extends. The result is that the position of the slot 6 in the tank can be disposed relative to the angle of the handle to insure 10 emptying and the tank can be held in this position by placing the inner end of screw 32 in the proper socket.

Referring again to the cutting knife, it will be seen that a diagonal rod 33 secured 15 across the upper side of the supporting frame serves as a mounting for the aforesaid spring-pressed latch 28. Also, if desired, the free ends of the knife may be upturned as shown at 34 to provide a finger piece for 20 convenient resetting of the knife.

I intend to use a supplemental tool 35 such as seen in Fig. 7 in conjunction with the machine. The spaced rubber covered 25 jaws 36 of the tool serve to grip the paper for pulling it through the machine at the starting of a new stretch and the rubber covered cross-bar 37 on the opposite end of the tool serves as a means for holding the paper against the wall to insure against 30 slipping. In using the tool, the cross-bar 37 is simply held against the lower end of the strip of paper at the beginning of the operation and in practice this cross-bar will be substantially the same width as the strip 35 of paper with which it is engaged. The rubber sleeves 38 and 39 on the cross-bar and jaws respectively prevent tearing of the paper.

In operation, the paper unwinds from the 40 roller 3, passes across the slot in the paste container, where paste is applied thereto, then passes over the guide bars 22 and 23 and around the brush 24 which is pressed against it to cause it to adhere to the wall 45 surface. When the end of a stretch of paper is reached, the pull cord controlling the latch 28 is pulled and the knife 26 automatically moves between the bars 23 to sever 50 the strip of paper. It is obvious that to change the degree of pressure of presser-bar against the paper, the cord 16 is manipulated.

When using the machine in the corners 55 of the room the type of brush described, must be removed and a different type, such as shown in Fig. 7 substituted therefor. Referring to this figure, it will be seen that the brush is indicated generally by the reference character 40. The aforesaid wheels are eliminated and the bristles 41 are so shaped as to permit the brush to press small strips of paper in corners of the room.

Although the machine has been described 60 as being of a specified size, I wish it to be

understood that it may be of any size and the details may be varied within the scope of the subjoined claims. I contemplate for instance making the machine up as a toy in some instances.

70

I claim:—

1. A wall-paper hanging machine comprising a support provided with guides over which the strip of paper travels, a container for paste mounted on said support, said container having a slot in one side thereof across which said paper passes, a spring-pressed bar disposed opposite said slot and extending the full length thereof for pressing the paper into same, and a manually controlled means for varying the pressure of said bar on the paper.

2. In a wall-paper hanging machine, a supporting structure, guides thereon over which the paper travels, a container for paste mounted on said support, said container being provided in one side with a longitudinal slot over which said paper passes, a spring-pressed bar coacting with that portion of the paper passing over said slot, a lever coacting with said bar for moving it away from slot and varying the pressure on said paper, and a flexible element connected with said lever.

3. A structure specified in claim 4, together with a plurality of anchoring pins with which the free ends of said flexible element can be selectively engaged for maintaining the bar in different set positions.

4. In a wall-paper hanging machine, a support having guiding means for the paper, a paste containing tank for applying paste to the reverse side of the paper, said tank being provided in one side with slot across which said paper travels, means for pivotally mounting said tank on said support to vary the position of the slot to facilitate emptying of the paste, and means for holding the tank in different set positions.

5. In a wall-paper hanging machine, a supporting frame, a container mounted on said frame for applying paste to the paper, a pair of adjacent vertically spaced bars over which the paper is adapted to travel, a cutting knife mounted on said frame for swinging movement between said bars, a spring connected with said knife for automatically swinging the same to an operative position for severing the paper by a shearing cut, means for holding the knife in an inoperative position against the tension of the spring and means for releasing said holding means to permit the spring to actuate the blade.

6. In a wall-paper hanging machine, a supporting frame, a pair of adjacent vertically spaced bars over which the strip of paper is adapted to travel, a spring-actuated knife adapted to swing between said bars

130

for severing the strip of paper, said knife being provided on one edge with a shoulder, a diagonal bar mounted on said frame, said knife being adapted for coaction with 5 said bar when in inoperative position, a spring-pressed latch carried by said bar and adapted to engage said shoulder for holding the knife in inoperative position, and a flexible pull-element connected with 10 said latch for retracting it to permit operation of the knife.

7. In a wall-paper hanging machine, a supporting frame, a bristle-brush rotatably mounted on the outer end of said frame, the 15 strip of paper being adapted to travel around said brush to permit the latter to serve in pressing it against the wall causing it to adhere thereto, the journals of said brush extending beyond said frame, wall-engaging wheels carried by the extending 20 portions of the journals, said wheels being of less diameter than the brush to cause the outer ends of the bristles of the latter to pro-

ject beyond the peripheries of the wheels.

8. A wall-paper hanging machine comprising 25 a portable support including a frame, a roller mounted on said frame on which the paper is adapted to be wound, guides on said frame over which said paper is adapted to be trained, pivotally mounted 30 adjustable paste container mounted on the frame adjacent said roller, said container having a slot in one side across which said paper is adapted to travel, a spring-pressed 35 adjustable presser-bar cooperating with that portion of the paper passing over said bar, vertically spaced bars over which said paper is adapted to travel, a spring-pressed manually released knife adapted to swing between 40 said bars severing the paper, a bristle brush mounted on the frame adjacent said bars and wall-engaging wheels carried by the journals of said brush.

In testimony whereof I have hereunto affixed my signature.

ALEXANDER FRITZ.
